HYDRAULIC PRESS

William P. Muir, Hampstead, Quebec, Canada, assignor to Dominion Engineering Works Limited, Lachine, Quebec, Canada

Application June 13, 1942, Serial No. 446,994
In Canada April 11, 1942

2 Claims. (Cl. 60—52)

1

This invention relates to control mechanism for regulating the "tonnage" or working pressure of a hydraulic press to suit the work being done and to prevent overloading of the work or tooling.

Various methods of regulating the "tonnage" or working pressure of hydraulic presses have been proposed and adopted prior to this invention. In some cases the discharge of a variable stroke pump which feeds the hydraulic press circuit is gradually reduced as the working pressure increases so that, when the desired maximum working pressure is attained, the pump stroke will be just sufficient to maintain this maximum pressure against leakage. In other cases the discharge of a variable stroke reversible pump feeding the hydraulic circuit is maintained substantially constant until the working pressure is built up to the required maximum value whereupon the pump discharge is stopped or reversed through the agency of a suitable pressure operated pump stroke neutralizing and reversing mechanism. In other cases pressure-operated controls are provided for automatically operating the main control valve of the press to transfer the pump discharge from the pressing cylinder to the return cylinder or cylinders when the working pressure in the pressing cylinder has been built up to the desired maximum value, such operation of the main control valve also serving to establish connections through which pressure fluid is relieved from the pressing cylinder during the return stroke of the press.

The foregoing and other methods of "tonnage" regulation now practiced are open to the objection that there is an appreciable time lag between the development of the desired maximum working pressure in the pressing cylinder and the actual operation of the pump stroke adjusting mechanism, control valve, or other control element relied upon to limit the rise of the working pressure. If there is any irregularity in the operation of such pump stroke adjusting mechanism, valve or other control element, the delayed action thereof may permit the working pressure to exceed the desired maximum value to a sufficient extent to overload the work or tooling. The method of regulation which involves the gradual reduction of the pump discharge as the working pressure increases is also open to the objection that it slows down the building up of the working pressure to the required maximum value and thus reduces the operating speed of the press.

With the foregoing in mind, an important object of this invention is the provision of adjustable "tonnage" or working pressure regulating mechanism which functions instantly and independently of the pump stroke controlling mechanism and the main control valve to prevent fur-

2

ther increase of the working pressure when the latter has been built up to a maximum value predetermined by the setting of said regulating mechanism.

5 A further object is to provide a "tonnage" or working pressure regulating mechanism which, in addition to the above mentioned characteristics, enables the full discharge capacity of the pump to be utilized in rapidly building up the working pressure to the required maximum value.

10 A further object is the provision of a "tonnage" or working pressure regulating mechanism which, while permitting the full discharge capacity of the feed pump to be utilized in building up the working pressure to the required maximum value, also includes means whereby the pump discharge is automatically reduced after the desired maximum working pressure is attained.

15 A further object is the provision of a "tonnage" or working pressure regulating mechanism including means for effecting either immediate or delayed operation of the main control valve from a power stroke to a return stroke position, the arrangement being such that any delay or lag in the operation of said valve to its return stroke position has no effect on the instantaneous operation of said regulating mechanism to prevent further increase of the working pressure when the latter has been built up to the desired maximum value.

20 A further object is the provision of a "tonnage" or working pressure regulating mechanism including means whereby the operation of the reversing valve to effect a return stroke of the press 25 may be delayed to permit the press to dwell on the work at constant pressure for as long as may be desired.

25 A further object is the provision of a "tonnage" or working pressure regulating mechanism which 30 functions automatically in direct and instant response to the development of a predetermined working pressure in the pressing cylinder and hydraulic circuit to prevent further rise of pressure by establishing a relief connection through which the full discharge of the pump may be bypassed even when the pump is operating at maximum discharge capacity. This protects both the press and the pump from overloading under any conditions of operation.

35 A further object is the provision of a "tonnage" or working pressure regulating mechanism including a main pressure regulating relief valve through which the discharge of the feed pump is bypassed when the working pressure in the pressing cylinder and hydraulic circuit reaches a predetermined maximum value and a supplementary back pressure regulating relief valve through which the discharge from the main relief valve is passed, said back pressure regulating valve serving to maintain in the portion of

the relief line located between said valves an intermediate pressure which is utilized, through the agency of suitable control mechanism, to operate the main control valve and/or the stroke regulating mechanism of the feed pump, said intermediate pressure being also available for the operation of other controls.

According to this invention, the maximum value of the working pressure developed in the hydraulic circuit and pressing cylinder during a working stroke of the press is predetermined by the setting of an adjustable pressure regulating valve which is normally closed to prevent flow of pressure fluid through a relief line included in the hydraulic circuit of the press. As soon as the working pressure in the hydraulic circuit and pressing cylinder is built up to the predetermined maximum value, the pressure regulating relief valve opens instantly so that the excess pressure fluid delivered by the hydraulic pump feeding the hydraulic circuit is by-passed through the relief line. The flow of pressure fluid through the relief line is also controlled by a back pressure regulating relief valve which is located at the discharge side of the main pressure regulating relief valve and is set so as to maintain a predetermined intermediate pressure in the portion of the relief line located between said valves. This intermediate pressure is utilized, through the agency of suitable pressure responsive mechanism, to effect either immediate or delayed operation of the main press controlling valve from a power stroke to a return stroke position, the arrangement being such that the operation of the main control valve to its return stroke position following the development of a predetermined working pressure in the hydraulic circuit may be delayed to permit the press to dwell on the work for as long a period as may be desired and without any resulting increase of the working pressure. The intermediate pressure thus established in the relief line may also be utilized to operate the stroke adjusting mechanism of the feed pump to reduce the discharge volume of the pump once the predetermined maximum working pressure has been developed in the hydraulic circuit and pressing cylinder. This automatic reduction of the discharge volume of the pump makes it possible to reduce the power consumption and the wear on the pump when the operation of the main control valve to its return stroke position is delayed to permit the press to dwell on the work for a long period.

Other objects, advantages and characteristic features of the invention will be more readily understood from the following detailed description taken in connection with the accompanying drawings, in which—

Fig. 1 is a diagrammatic view of a downstroking press assembly embodying my invention.

Fig. 2 is a view similar to Fig. 1, but showing a slight modification.

Referring more particularly to the drawings, 3 designates the movable platen of a conventional downstroking press. During the working or power stroke of the press the platen is moved downwardly by fluid pressure acting against the upper end of a main pressing ram 8 which works in the main pressing cylinder 7. During the return or non-working stroke of the press the platen is moved upwardly by fluid pressure acting against the lower ends of the pushback rams 9 which work in the pushback cylinders 8. The hydraulic circuit of the press includes a variable stroke hydraulic feed pump 10 and a main control valve

11, the latter comprising a ported valve casing 12 containing a longitudinally movable valve member 13 provided with annular grooves 14 and 15. When the valve member 13 is in the power stroke position shown in Fig. 1, the discharge from the pump 10 is conducted through line 16, valve casing port 17, valve groove 14, valve casing port 19 and line 20 to the pressing cylinder 7 where it acts against the upper end of the pressing ram 8 to move the platen 3 downwardly on its power or working stroke. At the same time fluid, previously supplied to the pushback cylinders 8, is discharged therefrom through line 22, valve casing port 23, valve groove 15, valve casing port 24, and relief line 25 to sump tank 26 or other suitable point of discharge. When the valve member 13 is shifted to the right from the position shown in Fig. 1, the pressure fluid previously supplied to the pressing cylinder 7 is relieved therefrom through line 20, valve casing port 18, valve groove 14, valve casing port 27 and relief line 25. At the same time the discharge from pump 10 is conducted through line 16, valve casing port 17, valve groove 14, valve casing port 23 and line 22 to the pushback cylinders 8 so that the fluid pressure thus applied to the lower ends of the pushback rams 9 causes an upward or return stroke of the platen 3. At the same time a portion of the fluid supplied to one of the pushback cylinders 8 is conducted through line 27a to a cylinder 28 where it acts to depress a plunger 29 which opens a prefill valve 30 against the resistance of the valve closing spring 31. The opening of the prefill valve 30 permits a portion of the fluid in the pressing cylinder 7 to be forced into the prefill tank 32 by the upstroke of the main pressing ram 8. The valve 30 is constructed so that, during the power stroke of the press, it opens against the resistance of the spring 31 to permit a rapid filling of the cylinder 7 by fluid which flows into said cylinder from the prefill tank 32 during the early part of the pressing stroke.

As the construction and operation of pressure operated prefill valves of this type is well known, the foregoing description is thought to be sufficient for present purposes.

The valve member 13 of the main control valve 11 is normally biased to a return stroke position by means of a biasing spring 33 confined between one end of the valve casing 12 and a collar 34 fixed to the stem 37 of valve member 13. The valve stem 37 is also connected, by a toggle 38, to a toggle operating lever 39 which is adapted for manual operation to either a toggle extending or toggle collapsing position. The component members of the toggle 38 are constructed so that, when the toggle is extended as shown in Fig. 1, it will retain its extended condition until collapsed by toggle collapsing movement of the lever 38 or by other means. This may be accomplished, for example, by constructing the toggle operating lever 39 and the toggle 38 as described in U. S. Patent 2,346,379, granted June 17, 1941, to Dominion Engineering Works Limited, assignee of William F. Muir.

When the toggle 38 is extended as shown in Fig. 1 it serves to hold the valve member 13 in its power stroke position against the resistance of the biasing spring 33. When the toggle 38 is collapsed by movement of the lever 38, or otherwise, it permits the spring 33 to shift the valve member 13 to its return stroke position which is to the right of the position shown in Fig. 1.

According to the present invention the inlet

port 40 of a main pressure regulating relief valve 41 is connected to line 20 by a suitable pipe connection 42. The discharge port 43 of valve 41 is connected, by suitable pipe connection 44, to the inlet port 45 of an auxiliary back pressure regulating valve 46, the discharge port 47 of which is connected, by pipe 48, to the previously mentioned relief line 25. The valve 41, pipes 42 and 44, valve 46 and pipe 48 conjointly provide a valve controlled relief line connection 10 between the main fluid line 20 of the pressing cylinder and the relief line 25. As here shown, valve 41 comprises a casing 49 containing a vertically movable valve 50 which is normally closed against its seat 51 by a valve closing spring 52, the compression of which may be varied by adjustment of the spring compressing nut 53. The valve member 46 also comprises a casing 55 containing a valve 56 which is held to its seat 57 by a valve closing spring 58, the compression of which may be regulated by adjustment of the spring compressing nut 60. From this it will be apparent that the valves 41 and 46 may be spring loaded by suitable adjustment of the nuts 53 and 60 to open when the fluid pressure acting to unseat said valves reaches a predetermined maximum value.

For present purposes it will be assumed that the spring loading of the valve 41 is adjusted so that this valve will open only when the working pressure developed in the hydraulic circuit and the pressing cylinder 7 during the working stroke of the press reaches a maximum value of approximately 2000 lbs. per square inch. The opening of this valve in response to the establishment of such pressure permits the excess discharge of the pump to be passed therethrough and thus prevents further rise of pressure in the hydraulic circuit and the pressing cylinder. In this connection it may be explained that the valve 41 is preferably made of sufficient size to by-pass the full discharge of the pump even when the latter is working at maximum discharge capacity. The discharge from the valve 41 passes through the auxiliary back pressure relief valve 46, the spring loading of which is adjusted to maintain an intermediate pressure of, say, 200 lbs. per square inch in the relief line connection 44 between the two valves. As hereinafter described the intermediate pressure thus established in the portion 44 of the pressure regulating relief line is utilized to operate the valve 11 and also the stroke regulating mechanism 10a of the feed pump 10. It is also available for operating other controls.

The intermediate pressure established in the portion 44 of the relief line is transmitted, through pipe 61 and valve 62, to a piston 63 operating in a cylinder 64 and serves to move the piston downwardly against the resistance of the piston biasing spring 65. The piston 63 is provided with a stem or rod 66 which, during the downward movement of the piston, acts against one of the members of the toggle 39 to operate the toggle to a collapsed position permitting the valve member 13 of valve 11 to be shifted to its return stroke position by its operating spring 35. When it is desired to permit the press to dwell on the work for a given period subsequent to the development of the desired predetermined working pressure, this is accomplished by operating the valve 62 to throttle the flow of pressure fluid through the line 61. In this way the collapsing of the toggle 39 by the downward movement of

the piston 63 may be retarded to provide the desired period of dwell.

The pipe line 61 is provided with a branch line 70 through which pressure fluid is delivered to the stroke control mechanism 10a of the pump 10 to reduce the pump discharge volume subsequent to the establishment of the desired predetermined working pressure in the hydraulic circuit and the pressing cylinder 7. In this connection it will be readily understood that the power consumption and the load on the pump is considerably reduced by reducing the volume of the pump discharge following attainment of maximum working pressure in the system. The flow of pressure fluid through the line 70 is controlled by a suitable regulating valve 71.

When the valve element 13 of the main control valve 11 is in its right hand or return stroke position the pressure regulating valves 41 and 46 are isolated since, in this position of valve element 13, the fluid line 20 is connected to the exhaust line 25. In the return stroke position of valve element 13, the intermediate pressure in pipe connections 44, 61 and 70 is relieved via bleed valve 72, pipe 48 and exhaust line 25.

In the foregoing arrangement the discharge from the main pressure regulating valve 41 is so regulated by the action of the auxiliary back pressure regulating valve 46 that the desired intermediate pressure in the portion of the relief line between the two relief valves is maintained constant from the moment the valve 41 opens until the press platen 5 is operated on its return stroke. Since this intermediate pressure is maintained practically constant irrespective of the volume of discharge through the valves 41 and 46 it provides an ideal source of hydraulic energy for operating the main control valve 11 and the pump stroke adjusting mechanism 10a.

It is important to note, at this point, that when the desired maximum working pressure is built up in the hydraulic circuit and the pressing cylinder 7, the valve 41 opens instantly to prevent further rise of this pressure. It will thus be seen that a very close regulation of the maximum working pressure developed in the system may be obtained by appropriate adjustment of the spring loading of valve 41 and that this regulation is not affected by any time lag in the operation of the main control valve 11 to its return stroke position nor by any time lag in the operation of the pump stroke adjusting mechanism 10a. Consequently, if the valves 41 and 46 are made of such size as to be capable of discharging the full capacity of the pump, it is possible to delay the operation of the main valve 11 to its return stroke position so as to permit the press to dwell on the work at constant pressure for as long as may be desired. During such dwell periods the by-passing of the full pump discharge through the valves 41 and 46 prevents overloading of both the press and the pump.

Another advantage of the arrangement described herein is that the maximum working pressure, as determined by adjustment of the valve 41, remains constant irrespective of the setting of the valve 46 or the rate of the flow through the valves 41 and 46. The utilization of the intermediate pressure established between the valves 41 and 46 for reducing the pump discharge makes it possible to economize power and to prolong the life of the pump when operating at long pressure dwells.

Fig. 2 shows another embodiment of the invention in which the stem of the main control

valve 13 is connected to an operating piston 15 working in an air cylinder 16. The operation of piston 15 is controlled by the action of a pilot valve 11 working in a pilot valve casing 18 to which air under pressure is delivered through a main air line 19. When the pilot valve is in the position shown in Fig. 2 air under pressure is delivered to the right hand end of cylinder 16 through pilot valve port 80, pilot valve casing port 81, and line 82, the air previously supplied to the right hand end of air cylinder 16 being exhausted through line 83 and a suitable exhaust connection 84 provided in the pilot valve 11. The air thus applied to the right hand end of cylinder 16 acts against the piston 15 to operate the main control valve 13 to the power stroke position shown in Fig. 2. When the pilot valve 11 is shifted to the left the line 83 is connected to the main supply line 19 through the pilot valve port 80 so that air under pressure is now supplied to the left hand end of cylinder 16 to operate the piston 15 and the main control valve element 13 to a return stroke position. During this latter operation of the piston 15 the air previously supplied to the right hand end of cylinder 16 is exhausted through line 82 and an exhaust port 85 provided in the pilot valve 11.

The pilot valve 11 may be operated manually through the agency of suitable normally closed push button valves 88 and 89. As here shown the inlet ports of these push button valves are connected in parallel with each other to the main air supply line 19 through the agency of a branch connection 90. The outlet port of valve 88 is connected to the left hand end of pilot valve cylinder 18 by a fluid line 91 while the outlet port of push button valve 89 is connected by pipe line 92 to the right hand end of the pilot valve cylinder 18. From this description it will be apparent that when push button valve 88 is opened against the resistance of its valve closing spring 88a compressed air will be applied to the left hand end of the pilot valve 11 to force the pilot valve to the right. Similarly, the opening of the push button valve 89 against spring 89a causes compressed air to be supplied to the right hand end of the pilot valve cylinder 16 to force the pilot valve to the left.

In the arrangement shown in Fig. 2 the intermediate pressure established in the section 44 of the work-pressure regulating relief line controlled by valves 41 and 46 is utilized to effect automatic operation of the pilot valve 11 in the direction necessary to operate the main control valve 13 to its return stroke position. In this connection it will be noted that the line 61 is connected to the left hand end of a cylinder 94 containing a piston 95 which is normally biased to the position shown in Fig. 2 by the spring 96. When the piston 95 is moved to the right by the intermediate pressure established in line 61 the stem 97 of said piston engages and opens a normally closed valve 98 which controls the flow of air through an air line 99 connecting the previously mentioned air lines 80 and 81. The opening of valve 98 permits compressed air to flow to the left hand end of the pilot valve cylinder 18 and to operate the pilot valve 11 to the right thereby establishing the connections necessary to operate the main control valve element 13 to its return stroke position. During the return stroke of the press the air supplied to cylinder 94 is exhausted through the bleed valve 12.

Having thus described what I now consider to be the preferred embodiment of this invention it will be understood that various modifications may be resorted to within the scope and spirit of the appended claims.

Having thus described my invention, what I claim is:

1. A hydraulic press including a main control valve through which pressure fluid is routed to effect a working stroke of the press in one position of said valve and to effect a return stroke of the press in another position of said valve, a collapsible valve-actuating toggle connected to said valve and serving, when extended, to hold said valve in its first mentioned working stroke position, a fluid pressure toggle-collapsing device comprising a cylinder and a piston working in said cylinder and connected to said toggle, biasing means arranged to shift said valve to the second mentioned or return stroke position upon collapse of said toggle by said piston, a fluid line through which pressure fluid is conducted from said valve to the pressing cylinder of the press in the working stroke position of the valve, an excess-pressure relief line connected to said first mentioned line at a point between the pressing cylinder and said valve, a normally closed working-pressure regulating valve arranged in said relief line and adapted to be instantly opened by the pressure fluid when the working pressure in the pressing cylinder is built up to a predetermined maximum value, said relief line and pressure regulating valve being of sufficient capacity to carry off from said first mentioned line all the pressure fluid in excess of that required to maintain the said predetermined maximum working pressure in said pressing cylinder, a back pressure regulating valve included in said relief line at the discharge side of the working-pressure regulating valve and functioning, in the open position of said working-pressure regulating valve, to maintain a definite intermediate pressure in a portion of the relief line located between said valves, a valve-controlled fluid transfer line connected between the cylinder of the toggle collapsing device and the portion of the relief line located between the discharge side of the working-pressure regulating valve and the inlet side of the back pressure regulating valve and a valve-controlled by-pass line having one end connected to said fluid transfer line and the other end connected to said relief line at the discharge side of the back pressure regulating valve.

2. A hydraulic press as set forth in claim 1 including a variable stroke hydraulic pump having its discharge side connected to said main control valve to supply pressure fluid to the pressing cylinder of the press in the working stroke position of said valve, said pump being equipped with a pressure responsive stroke adjusting mechanism and a pressure fluid line through which working fluid is supplied to and exhausted from said mechanism, said line being equipped with a control valve and being connected between said stroke adjusting mechanism and the aforesaid fluid transfer line through which fluid is supplied to and exhausted from the cylinder of the toggle collapsing device.

WILLIAM P. MUIR.
